US0D1096697S

(12) **United States Design Patent** (10) **Patent No.:** **US D1,096,697 S**
(45) **Date of Patent:** **** Oct. 7, 2025**

(54) **SPEAKER AND SHELF SET**

(71) Applicant: **Sonos, Inc.**, Santa Barbara, CA (US)

(72) Inventors: **Dylan Entelis**, Los Angeles, CA (US);
Matthew Malone, Los Angeles, CA (US);
Zachary Scott, Oakland, CA (US)

(73) Assignee: **SONOS, INC.**, Goleta, CA (US)

(**) Term: **15 Years**

(21) Appl. No.: **29/913,703**

(22) Filed: **Oct. 6, 2023**

Related U.S. Application Data

(63) Continuation of application No. 29/763,146, filed on Dec. 21, 2020, now Pat. No. Des. 1,006,487, which is a continuation of application No. 29/665,018, filed on Sep. 28, 2018, now Pat. No. Des. 906,009.

(57) **CLAIM**

The ornamental design for a speaker and shelf set as shown and described.

DESCRIPTION

FIG. 1 is a perspective view of a speaker and shelf set.

FIG. 2 is another perspective view thereof.

FIG. 3 is a front elevation view thereof.

FIG. 4 is a rear elevation view thereof.

FIG. 5 is a side view thereof.

FIG. 6 is an opposite side view thereof.

FIG. 7 is a top plan view thereof; and,

FIG. 8 is a bottom plan view thereof.

The broken lines represent portions of the speaker and shelf set that form no part of the claimed design.
